YARN PRINTING MACHINE

Joseph D. Kreis, Cleveland, Ohio, assignor to The Erie Dyeing & Processing Co., Cleveland, Ohio, a corporation of Ohio

Application May 4, 1932, Serial No. 609,162
Renewed October 4, 1934

20 Claims. (Cl. 101—172)

This invention relates to machines for printing yarn, and similar textile fibers incident to weaving or knitting the latter into fabrics of the character in which the appearance of tweed is simulated or in a fabric having a predominating color mottled with an irregularly appearing tracer thread or mark as exemplified in Figure 20 of the drawings herein.

Those skilled in the textile industry are familiar with the fact that such effects may be obtained by employing a yarn or thread having irregularly-spaced applications of color dye extending throughout the length thereof. It is essential that these dyed portions be irregularly spaced, otherwise, certain of the dyed areas will become massed when the yarn or thread is knitted or woven and the resultant fabric will attain an undesirable and uncontrollable shade or pattern which may vary in tone design or texture, as for instance certain areas may be mottled, others may attain a figure, stripe or pattern while still others may differ substantially in color and give an odd or unsightly appearance to the fabric.

Heretofore, as far as I am aware, the only method for the irregular printing of yarn or thread for these fabrics which has been found practical in the textile industry has been to employ manual or hand labor, the attendants stamping or printing the textile fibers in a haphazard manner to produce the desired irregularly spaced dyed marks. Such practice is not only expensive but, as will be obvious, results in regular spacing of the dyed portions at periods, since it is impossible for a laborer to properly gauge or time the stamping or printing operation without slowing down the work to a point where the product would be prohibitively expensive.

The primary object of the present invention, therefore, is to provide a highly efficient, practical machine which will print or dye irregularly-spaced marks of variable length upon the yarn or thread consistently day in and day out, the machine being capable of producing many and varied irregularly-spaced portions or "spots" along the length of the yarn or thread, which latter may be subsequently knit, woven or otherwise made up into fabrics having an attractive mottled appearance.

The foregoing and other objects and advantages will be rendered apparent in view of the following description taken in conjunction with the drawings, wherein:

Figures 1 and 2 are, respectively, views in plan and side elevation of a yarn or thread-printing machine embodying the features of the invention

in preferred form, certain parts of Fig. 2 being removed to show the frame construction;

Figs. 3 and 4 are sectional views taken substantially on the planes indicated by the lines 3—3 and 4—4, Fig. 2;

Fig. 5 is an end elevation of the parts shown in Fig. 6;

Fig. 6 is an enlarged detail fragmentary sectional view taken substantially on a plane indicated by the line 6—6, Fig. 2;

Fig. 7 is a view similar to Fig. 6, showing in further detail the parts illustrated in Fig. 4;

Figs. 8 to 18, inclusive, are enlarged detail views of certain parts of the machine which are more or less intimately concerned with the features of the invention;

Fig. 19 is an enlarged sectional view taken on the line 19—19, Fig. 4; and

Fig. 20 is illustrative of one of the types of fabric that may be produced by yarn or thread printed by the machine embodying the present invention.

Referring in detail to the drawings, and first generally to Figs. 1, 2 and 3, the machine in its entirety comprises a plurality of printing units which are supported in series on channel base members 5, the units being inner-gearied for synchronous operation. Since these units are substantially identical, a description of one will suffice for all. Each unit embodies a dye-feeding roll A, an absorbent or pad roll B, and a printing roll C, which are provided with shafts or spindles 6, 7 and 8 journaled in suitable bearings borne by the frame of the machine. The upper and lower rolls C and A are mounted in adjustable hanger brackets 9 and 10 carried by side frame stanchions 12 and a transversely disposed spacer frame member 13, and the roll B is carried directly by the said frame members 12. The rolls of each unit are driven by means of gears 14, 15 and 16 affixed upon the outer ends of the spindles 6, 7 and 8, respectively. The machine units (four in the present instance) are inter-gearied by means of idler gears 17, each of which is mounted on a shaft having bearing in one of the stanchions 12. The hanger brackets 9 which carry the rolls A are supported at one extremity thereof by the stanchions 12 and at their opposite ends through the medium of links 18 which are screw threaded and provided with hand wheels 19, to provide for adjustment of each of the said rolls relative to the rolls B; roll B is stationarily mounted with respect to the rolls A and C, while the hanger bracket 10 for roll C is adjustably and resiliently supported at its opposite extremities upon pivotally mounted rods 20 which are provided with

60

110

screw threaded ends having hand wheels 21 thereon to regulate the tension upon the springs 22. The roll A is partly submerged in fluid dye compound carried by a reservoir or dye pan 23, 5 which is mounted on brackets movably supported by the side frame members 9. These brackets are provided with racks 24 adapted to mesh with gears 25 mounted upon a cross shaft 26. A hand wheel 27 is affixed to the one end of the shaft 26 10 to facilitate adjustment of the pan relative to the roll A. The dye or coloring material may be supplied to the pans by means of a funnel 28 which is associated with a pipe line or conduit 29.

The yarn or thread, indicated at Y, is fed into 15 the machine over a suitable guide 30 and passes downwardly and around a tension roll 31, doubles back over a second tension roll 32 and then between the rolls B and C of the first printing unit. The roll 31 is carried by a pivotally mounted 20 hanger bracket 31a which is adjustably supported at one extremity thereof by rods 31b having threaded end portions upon which hand wheels 31c are mounted. Mounted at the outgoing end of the machine is a reel 33 which is carried upon 25 pivotally mounted brackets 34, provided with an adjusting screw 35.

The present invention is primarily concerned with the printing roll C, its appurtenances and cooperating parts whereby the desired irregular 30 printing of the yarn or thread is obtained, and the following description is confined and directed more or less in detail to this organization.

The roll C is preferably made up of an assembly 35 comprising the shaft 8 (Figures 4 and 19) shown formed with a plurality of annular clearance grooves 36a and longitudinally extending keyways 36b and 36c; a plurality of longitudinally reciprocable cam members or bars 37, each having a plurality of cam faces or teeth 37a formed 40 on the outer surface thereof; a like number of similarly shaped radially-reciprocable cam bars 38 having cams or cam teeth 38a adapted to coact with the teeth 37a; a plurality of readily removable and replaceable printing plates or rails 45 39 secured on the outer faces of the bars 38; and combined cam-bar guides and retainer members 40 and 40a which are splined on the opposite ends of the shaft 36 and retain the foregoing members in operative assembled relation.

50 One of the members 40, 40a is shown in detail in Figs. 10 and 11. The inner face of each member is formed with a plurality of radial cam-bar guide grooves 40b, and the circumferential portion of the face of said member with grooves 40c bounded by lugs 40d. The central portion of the member 40 is provided with a plurality of guide bores 40e for a purpose to be described.

There is a groove or track 40b for each set of 60 cam bars 37, 38 so that when the end members 40, 40a are mounted upon the shaft 36, these bars will register with the grooves, each of the outer bars 38 reciprocating radially in its respective guideway or groove.

65 The bars 38 are normally urged radially inwardly by means of the spring assembly shown in Fig. 7. Each bar 38 is recessed at its opposite ends to receive a shoe forming part of a spring housing assembly comprising telescoping cylinders or 70 blocks 41 and 41a, a spring 41b, and a pin 41c. As shown, a separate assembly is provided for each bar 38 in both the end members 40 and 40a, but it will be obvious that this is a matter of design and may be varied as found expedient.

75 By referring to Fig. 19, it will be noted that

there are twenty-four cam bars and a like number of printing bars in the example shown.

The printing bar actuating mechanism is governed primarily by "hunting" gear mechanism including one or more cam plates or hunting gear members 42 and 42a, note Figs. 14 and 15, 80 which are formed with teeth 42b and 42c to effect, in conjunction with an internally toothed gear unit, an intermittent movement of the parts co-ordinated therewith. In the example shown, there are twenty-seven teeth in the gear 42 and twenty-five in gear 42a. One or a set of these cams or gears are mounted for free rotation on bearings 44 carried by one extremity of a fixed shaft 43, which extends across the machine and is supported at each side by the brackets 10 and frame member 13. These hunting gear members 42 and 42a transmit motion to a plurality of radially movable plungers 45, one of which is shown in detail in Fig. 8. These plungers are mounted in grooves or guideways in a spider gear 46, which is formed on its inner face with a plurality of radial grooves 46a bounded by teeth 46b, note Figs. 16 and 17. The gear 46 rotates about a stationary retainer plate 47, which is fixed on 90 the end of shaft 43 by means of a nut 48. The gear 46 and plungers 45 are held in operative assembled relation by means of an inner retainer plate 49 which is fixed to the gear 46 by bolts 50 and is mounted on bearing 51 on the end of 100 the shaft 43, said plate being formed with an annular flange 49a adapted to engage stop shoulders 45a formed on the plungers 45. The hunting gears 42, 42a, are mounted intermediate the revolving retainer member 49 and the stationary end retainer plate 47. As shown herein, there are an even number (26) of radial grooves 46a in the gear 46 and consequently an even number of plungers 45, and there are an odd number of teeth in the hunting gears 42, 42a. These co-acting teeth and plunger units should respectively be either odd or even, that is, if there are 110 an odd number of teeth there should be an even number of units, or vice versa, for a purpose which will soon become apparent.

The gear 46 is in constant mesh with a gear 52 (shown in detail in Figs. 12 and 13), which is formed with a plurality of slots 52a and adjustably secured to the printing roll gear 16 by means of bolts 53. The inner face of the gear 125 52 is radially grooved as at 52b at its periphery, forming a plurality of brackets 52c. A coacting retainer plate 54 (see Fig. 13a) is provided as part of the assembly and is formed on its face with a plurality of radially extending concave 130 grooves 54a and a series of holes 54b circumambient its axis and adapted to register with the bores 40e in the member 40. A plurality of dogs or levers 55, (one for each printing bar, or twenty-four) are pivotally mounted on a ring 135 56, which is supported in grooves 57 formed in the brackets 52c, said grooves providing a complete annular groove for said ring. The gear 52 is formed with bolt holes 57a and the retainer plate 54 is secured against the inner face of the 140 said gear, with the concave grooves 54a in aligned registration with the grooves 52b, the body portion adjacent the groove thereby effecting a closure of the grooves 57. The dogs or levers 55 are thus pivotally suspended and permitted a limited oscillatory movement between the parts 54 and 52, as shown particularly in Fig. 6. The back of each dog is formed with a contact surface 55a which is adapted to engage an 145 annular stop shoulder 57b formed on the gear 52. 150

The dogs 55 transmit rectilinear motion to the cam bars 37 by means of plungers 58, which are mounted for free sliding movement in the aligned bores 40e and holes 54b formed in the members 40 and 54, note particularly Fig. 6.

The entire printing-bar-actuating mechanism above described is shown herein mounted at the right-hand side of the machine and is protected by a housing or guard 59, see Fig. 2. The cam bars 37 are actuated in reverse reciprocation by plungers 60 disposed at the left-hand end of each printing roll C, note Fig. 4. These plungers are mounted to slide in bores formed in the end retainer member 40a and are progressively engaged by a cam 61 formed on a cam plate 62, see also Fig. 18, which is held stationary with respect to the roll. Cam 61 continually returns any of the bars 37 that may have been actuated during rotation of the printing roll to a retracted position, and consequently retract the dogs or levers 55 back against the plungers 45.

The operation of the machine is substantially as follows:

The yarn or thread Y upon being fed in from the left-hand end of the machine passes between the dye roll B and the printing roll C of each unit. Dye roll B is provided with a felt or like absorbent covering b which is continually fed with dye by the feed roll A, and the printing bars 39 are adapted to press the yarn against this felt upon being actuated radially by cam bars 37 and 38.

As the gear 46 rotates, the plungers 45 engage the teeth of the hunting gear members 42, 42a. Certain of these teeth are shallow, as at 42c. These may be considered as printing teeth, since when a plunger 45 engages therein, the plunger is moved radially and in turn actuates one of the dogs 55, plunger 58, cam bars 37 and 38, thus driving a printing rail 39 outwardly, so that upon further rotation of the roll C, said rail will bear against the roll B.

As the gear 46 rotates, the plungers 45 gravitate between the teeth of the hunting gear members 42, 42a, or in other words, have a floating engagement with said teeth except when the plungers strike the dogs 55, thus permitting relative angular movement between the said hunting gear members and the plungers. When a plunger is driven radially outwardly by a tooth 42c into engagement with a dog 55, a change takes place in the relative angular position of the hunting gear with respect to the plunger, due to the fact that the number of teeth of the gear is prime with respect to the number of plungers.

Since the hunting gears 42, 42a are provided with a number of teeth, which is prime with respect to the number of plungers 45, the said gears will be advanced or retarded for each revolution of the gear 46, depending upon the number of teeth in gears 42, 42a, relatively to the number of plungers 45. In the example shown, the gear 42 having twenty-seven teeth will be retarded one tooth per one revolution of said gear and the gear 42a having twenty-five teeth will be advanced one tooth per revolution of said gear. In this instance the product of 25×27 gives a number which, when multiplied by a number less than twenty-four, (the number of printing bars) and divided by twenty-four, gives a whole number. For example, 25×27 equals 675; 675×8 equals 5400; 5400 divided by 24 equals 225, a whole number. Thus in the present case the printing teeth will not repeat in a number of revolutions equal

to the product of $25 \times 27 \times 8$, considering one printing bar only.

Let us assume, however, that the hunting gear 42 has twenty-nine teeth and gear 42a has thirty-one teeth, a combination whose product when multiplied by any number up to twenty-four and divided by twenty-four gives a quotient ending in a fraction. Then the printing teeth 42c would not repeat in the cycle for a number of revolutions equal to the number of printing bars times the number of teeth in each hunting gear, or the product of $24 \times 29 \times 31$, neglecting the spacing of the printing strokes. This event is timed to occur with respect to one printing bar. If the bar cycle occurs once in say every $18\frac{1}{2}$ inches of yarn or thread, then repetition of that particular mark will not reoccur linearly for a number of revolutions equal to the product of $18\frac{1}{2} \times 24 \times 29 \times 31$. This number may be increased simply by adding additional hunting gears or cam plates each having an odd number of teeth and having a circumferential arrangement of shallow printing teeth which differ with respect to the teeth and the allocation thereof in the adjacent gears or cam plates. This number or the increments of the variable combinations may be organized to reach an indefinite number of cycles before repetition occurs as, for instance, by spacing the printing bars different distances from one another, or in staggered relation on the respective rolls; by using varying colors for each roll; varying the shapes of the printing bars, and other methods considered as a matter of mechanical skill and arrangement of parts coming within the scope of the invention as defined by the appended claims.

What I claim is:—

1. In a machine of the class specified, a printing roll, a plurality of printing bars mounted for limited radial movement on said roll, means for driving said roll, and means for actuating said bars, said latter means including a hunting gear and a plurality of radially-movable motion-transmitting units mounted around and having relative angular shifting movement with respect to the teeth of the gear, said gear having teeth adapted to co-act with said units, the sum of the teeth relative to the units being a prime number.

2. In a machine of the class specified, a printing roll, a plurality of printing bars mounted for limited radial movement on said roll, means for driving said roll, and means for actuating said bars, said latter means including a hunting gear and a plurality of radially-movable motion-transmitting units mounted around and having relative angular shifting movement with respect to the teeth of the gear, said gear having teeth adapted to co-act with said units, the number of co-acting teeth and units bearing a prime relation one with respect to another.

3. In a machine of the class specified, a printing roll, a plurality of printing bars mounted for limited radial movement on said roll, means for driving said roll, and means for actuating said bars, said latter means including a hunting gear and a plurality of radially-movable motion-transmitting units mounted around and adapted to have relative angular shifting movement with respect to the teeth of the gear, said gear having teeth adapted to co-act with said units, there being an odd number of teeth and an even number of units.

4. In a machine of the class specified, a printing roll, a plurality of printing bars mounted for limited radial movement on said roll, means for

- driving said roll, and means for actuating said bars, said latter means including a hunting gear and a plurality of radially-movable motion-transmitting units mounted around and adapted 5 to have relative angular shifting movement with respect to said gear, the ratio of gear teeth and units being such as to either advance or retard the gear relatively to the units for each revolution thereof.
- 10 5. In a machine of the class specified, a printing roll, means for rotating said roll, a plurality of printing bars mounted for limited radial movement on said roll, and means for actuating said bars during rotation of said roll, said means including one or more mutilated hunting gears and a plurality of co-acting radially-movable motion-transmitting units mounted around and having relative angular shifting movement with respect to the teeth of said gears.
- 15 6. In a machine of the class specified, a printing roll, means for rotating said roll, a plurality of printing bars, bar actuating cam members mounted for coaxing limited radial and longitudinal movement on said roll for imparting radial 25 printing movement to said printing bars, a plurality of radially movable plungers, means having a positive driving connection with said roll for supporting said plungers, a hunting gear provided with teeth adapted to co-act with said 30 plungers, and means for transmitting motion from said plungers to said printing bar actuating members.
7. In a machine of the class specified, a printing roll, means for rotating said roll, a plurality 35 of printing bars mounted for limited radial movement on said roll, a plurality of cam bars for actuating said printing bars, said cam bars being mounted for longitudinal movement with respect to said roll; and means for actuating said 40 cam bar including a mutilated hunting gear and a plurality of radially movable plungers mounted around said gear, said gear having teeth adapted to co-act with said units and being free to have relative angular movement with respect thereto, 45 and a gear member for carrying said units having a positive connection with said printing roll, there being a prime number of co-acting teeth relative to the number of units.
8. In a machine of the class specified, a printing 50 roll assembly comprising a supporting shaft, a plurality of cam bars mounted for longitudinal movement around said shaft, a plurality of printing bars supported for radial movement by said cam bars; and means for imparting longitudinal reciprocating movement to said cam bars comprising a plurality of pivoted members mounted for positive rotation with said printing roll, a plurality of radially movable plungers for actuating said pivoted members, and one or more relatively 55 movable hunting gears co-acting with said plungers, the total number of teeth of said latter gears and the total number of plungers being prime one with respect to the other to thereby produce relative angular movement between the 60 hunting gears and plungers during each revolution of the hunting gears.
9. In a machine of the class specified, a printing 65 roll assembly comprising a main supporting shaft, a plurality of longitudinally movable cam bars mounted around said shaft, a plurality of co-acting printing bars mounted for radial movement on said cam bars, a gear for driving said roll, a plurality of pivotally mounted dogs mounted for positive rotation with said gear and adapted to 70 transmit motion to said cam bars, a further gear 75 connected to said printing roll gear, a plurality of radially movable plungers carried by said latter gear and adapted to engage said dogs, and one or more hunting gears mounted for free rotation with respect to said plunger-carrying gear and provided with teeth adapted to co-act with said plungers, the teeth in said hunting gear being greater or less by an odd number than the number of plungers.
10. In a machine of the class specified, a printing roll, a plurality of radially movable printing bars carried by said roll, a plurality of longitudinally movable cam bars adapted to actuate said printing bars, and end retainer members provided with radial guide ways for said printing bars, means carried by said retainer members for normally urging said printing bars to retracted position, and means for actuating said cam bars to move said printing bars into printing position; said means comprising a plurality of pivotally mounted dogs having a positive connection with said printing roll, a plurality of co-acting radial movable units rotating adjacent to and in synchronism with said dogs, and a relatively angularly movable hunting gear for actuating said units, said gear being provided with a plurality of printing teeth and a plurality of non-printing teeth, the total number of teeth of said gear and the total number of units bearing a prime relation to each other to produce relative angular movement therebetween.
11. A printing roll assembly for yarn or thread printing machines comprising a main supporting shaft, a plurality of longitudinally reciprocating cam bars, a plurality of radially reciprocating printing bars, end retainer members provided with radial guide ways for said bars, a relatively stationary cam at one end of said roll for normally urging said cam bars in one direction, and means at the opposite end of said roll for moving said bars in the opposite direction, said means comprising a gear secured on the end of said shaft and provided with a plurality of pivotally mounted dogs and an idler gear in mesh with said last named gear, said idler gear carrying a plurality of radially movable plungers adapted to engage said dogs and one or more hunting gears mounted within said idler gear and adapted to actuate said plungers.
12. In a machine of the class specified, a printing roll, a plurality of radially movable printing bars carried by said roll, a gear secured on one end of said roll, and an idler gear in mesh with said first named gear, said idler gear carrying one or more relatively movable hunting gears and a plurality of radially movable plungers mounted for positive rotation with the idler gear, the number of teeth of said hunting gear being greater or less by an odd number than the number of plungers, and means for transmitting motion from said 125 plungers to said printing bars to actuate the latter.
13. In a yarn or thread printing machine, a printing roll assembly comprising a shaft, pairs of co-acting longitudinally and radially movable cam bars mounted around said shaft, one bar of each pair being longitudinally movable and its coaxing bar being radially movable, said bars being provided with co-acting cam teeth on the opposed faces thereof, means for irregularly actuating one bar of each pair longitudinally of said roll to impart radial movement to its co-acting bar, and printing bars secured on said radially moving bars.
14. In a yarn or thread printing machine, a 130

- printing roll, radially movable printing bars on said roll; and means for actuating said bars comprising a longitudinally movable cam bar, a gear secured on the end of said roll, said gear being provided with a plurality of pivotally mounted dogs, an idler gear in constant mesh with said first named gear, said idler gear being provided with a plurality of radially extending grooves, a plurality of plungers mounted in said grooves, and one or more hunting gears mounted on the same axis as said idler gear, said hunting gears being mounted for relative movement with respect to said idler gear and being provided with teeth which co-act with said plungers, the relative ratio of teeth and plungers being such as to advance or retard each hunting gear during one revolution of said idler gear.
15. In a yarn or thread printing machine, a plurality of printing units mounted in series, each 20 of said units comprising a dye feeding roll, a dye roll and a printing roll, said rolls being geared for synchronous rotation; an idler gear connected for positive rotation with and adjacent to said printing roll, one or more hunting gears mounted 25 for relative free rotation on the same axis as said idler gear, said idler gear carrying a plurality of radially movable freely slidable plungers adapted to engage the teeth of said hunting gears during part of a revolution of the latter, a plurality of 30 pivotally mounted dogs connected to said printing roll, a radially movable printing bar for each of said dogs, and means for transmitting motion from said dogs to said printing bars to actuate the latter.
35. 16. A printing roll assembly for yarn or thread printing machines comprising a plurality of radially movable printing bars, a plurality of bodily rotating radially movable units, means for transmitting motion from said units to said bars, and a relatively rotatable hunting gear for actuating said units, said gear being provided with teeth whose number is greater or less than the number 40 of said units and prime with respect to the latter.
17. A printing roll assembly for yarn or thread printing machines comprising a plurality of radially movable printing bars, a plurality of bodily rotating radially movable units, means for transmitting motion from said units to said bars, and a relatively rotatable hunting gear for actuating said units, said gear being provided with teeth
- which co-act with and whose number bears a prime relation to the number of units.
18. A printing roll assembly for yarn or thread printing machines comprising a supporting shaft, a plurality of longitudinally movable cam bars mounted on said shaft, a plurality of radially movable cam bars adapted to co-operate with said longitudinally movable bars, printing bars secured on said radially movable bars, end retainer members provided with radial guide ways for said radially moving bars, spring means adapted to normally urge said last named bars radially inwardly against said first-named bars, a cam for normally urging said longitudinally movable bars in one direction; and means for normally urging said bars in the opposite direction, said means comprising a plurality of pivotally mounted dogs, a gear connected to said printing roll shaft for carrying said dogs, and an idler gear connected to said first named gear, said idler gear being provided with a plurality of radially movable plungers; and means for actuating said plungers, said means comprising one or a plurality of hunting gears which have a free floating action on the same axis as said idler gear and are provided with a plurality of teeth adapted to co-act with said plungers and transmit motion to said dogs, the number of teeth of each hunting gear and the number of plungers being prime with respect to one another.
19. In a yarn or thread printing machine, means for irregularly printing the yarn or thread including one or a plurality of hunting gears provided with teeth which have a certain number thereof shallow in depth to act as printing teeth, printing bars or analogous members, and means for transmitting motion from said printing teeth to said bars, said latter means including a plurality of cam elements mounted around said hunting gears and having relative angular shifting movement with respect to the teeth of the gears.
20. In a yarn or thread printing machine, means for irregularly printing the yarn or thread including an idler gear which houses and carries therewith a plurality of radially movable units, and one or a plurality of hunting gears mounted for relative angular movement on the same axis as the idler gear and provided with teeth adapted to co-act with said units.
